UNITED STATES PATENT OFFICE

AARON WOLF, OF HARTFORD, CONNECTICUT

CLOTHES DRIER FOR INDOOR USE

Application filed December 2, 1930. Serial No. 499,444.

My invention relates to clothes driers for indoor use.

More particularly, stated, my invention relates to an improved fixture to be mounted in a kitchen or other room of a house, this fixture being preferably in the form of a casing and provided with a number of clothes arms to be detachably fitted into it and thus supported, the parts being adapted for enabling the clothes arms to be removed and replaced relatively to the fixture, thus facilitating the removal and replacement of garments upon the clothes arms.

While my improved casing and clothes arms associated therewith may be made up in different forms as required, I here illustrate and describe only a single form, which may be considered as typical and in which I use a casing somewhat in the form of a rosette and clothes arms adapted for this casing.

Reference is made to the accompanying drawing forming a part of this specification, and in which like letters indicate like parts throughout all of the figures.

Figure 1 is a side elevation of one form of my improved clothes drier.

Figure 2 is an inverted plan or bottom view of the same, the globe plate not being shown.

Figure 3 is a section on the line 3—3 of Figure 2, looking in the direction indicated by the arrows.

Figure 4 is a fragmentary view, partly a side elevation and partly a section, showing one of the clothes arms and a hand stick used in connection therewith.

Figure 5 is a fragmentary perspective of another form of my device.

A casing 5, made of metal, is mounted upon a support 6 of any appropriate kind. This casing 5 is provided with an outer wall 7 of annular form, and with an inner wall 8 also of annular form, these two walls being concentric, as may be understood from Figure 2.

A globe plate 9 is mounted upon the outer wall 7, and is used to conceal the internal structure of the casing, and may be used in connection with an electric lamp or the like, to be mounted within the inner wall 8, this lamp not being shown.

The outer wall 7 is provided with a rib 10

integral with it and of sinuous form, as shown in Figure 1. This rib strengthens the outer wall and renders the same more or less ornamental.

The outer wall 7 is also provided with openings 11, spaced equidistant and disposed radially.

Connected with the inner wall 8 and radiating outwardly therefrom to the outer wall 7 are a number of tubular sockets 12, 12. Each of these sockets has the form of a hollow truncated cone, the hollow of which, at its outer end, is of slightly greater diameter than any one of the openings 11.

Each socket 12 is provided with ends 13 and 14, its outer end being larger than its inner end, each socket extending outwardly to some one of the openings 11, and covers the same, so that the hollow of the socket at the outer end 13 thereof merges into the adjacent opening 11, and is slightly eccentric to this opening. The arrangement is such that a portion 15 of the outer wall 7, bounded by the opening 11, extends slightly above the lower level of the hollow of the socket, as indicated in Figure 4, for the purpose of normally preventing the removal of the clothes arms, as hereinafter more fully described.

I provide a number of clothes arms 16, each being a straight stick of wood of cylindrical form. Mounted upon one end of each clothes arm 16 is a button 17, made preferably of rubber and of any appropriate form, serving as a barrier to prevent the garments to be dried from slipping off the end of the clothes arm. This button also serves to prevent the garments from touching the ceiling.

Each clothes arm is further provided with a notch 18, for engagement with the extending portion 15 of the outer wall 7, as indicated in Figure 3.

When any clothes arm 16 is resting in its normal position it is strictly level, and engages the inner bottom surface of the tubular socket 12 throughout the entire length thereof.

To remove the clothes arm, its outer or free end is raised in order to disengage the notch 18 from the extending portion 15 of the outer wall 7; and this done, the clothes arm is

55

pulled radially outward from the casing and thus disengaged.

In order to facilitate the removal and replacement of the clothes arm 16 it is provided with a collar 19, made in halves held together by bolts 20, and provided with a mouth 21 of substantially funnel shape, as indicated in Figure 4.

I provide a hand stick 22, having a tapered end portion 23, to be used as indicated at the left of Figure 1 and also in Figure 4.

In practice the operator thrusts the end portion 23 of the hand stick 22 into the mouth 21, or, what is essentially the same thing, fits the mouth 21 over the end portion 23; and then, by means of the hand stick 22, raises the clothes arm 16 to the proximate level of the casing 5. This done, by slightly tilting the clothes arm 16 as indicated by dotted lines

20 at the left of Figure 3, the operator thrusts an end portion of the clothes arm into the opening 11 and brings the notch 18 down upon the extending edge portion 15, thus leaving the clothes arm horizontal, and there-

25 fore level.

To remove the clothes arm from the casing the operator simply follows the same steps inversely. That is, the hand stick is first thrust into the mouth 21, next raised, and then moved away from the casing.

The garments 24 and 25 to be dried are placed upon any or all of the clothes arms and the latter are then lifted into position as above described. When the garments have 30 dried out, they are taken down by removing the clothes arms as above described.

In removing and replacing the clothes arms, the button 17 tends to prevent the garments from touching the ceiling. For this 40 purpose the button may be made of any appropriate form.

In Figure 5 I show another form of my improved clothes drier. In this instance a fixture 26 is provided with walls 27 and 28 45 integral with it. These parts constitute a casing, which may be cast, pressed or stamped in a single integral piece, as required.

This casing is provided with an opening 50 and carries a tubular socket 12, this opening and socket being of substantially the kind above described with reference to Figure 3.

The form shown in Figure 5 may be mounted in any suitable manner. For instance one 55 or any larger number of these casings may be mounted upon a wall so as to project therefrom parallel to each other; or they may be secured to the ceiling, in any desired number.

Except as otherwise indicated, the structure and action of the form shown in Figure 5 is like that of the other form shown in Figures 1 to 3 and above described at length.

I do not limit myself to the precise construction shown, as variations may be made 60 therein without departing from my inven-

tion, the scope of which is commensurate with my claims.

Having thus described my invention, what I claim as new and desire to secure by Letters Patent is as follows:

1. A clothes drier for indoor use, comprising a casing having an annular inner wall and an annular outer wall disposed concentrically, the outer wall being provided with a plurality of openings, and a plurality of socket tubes equal to the number of said openings and connected with said inner wall and extending radially outward therefrom to said openings, the hollow of each socket tube communicating with one of said openings in said outer ring, and a plurality of clothes arms to be detachably thrust through said openings and into said socket tubes, and thus supported.

2. A clothes drier for indoor use, comprising a casing having an annular inner wall and an annular outer wall disposed concentrically, the outer wall being provided with a plurality of openings, and a plurality of socket tubes equal to the number of said openings, said socket tubes being connected with said inner wall and extending radially outward therefrom to said outer wall, the hollow of each socket tube communicating with one of said openings, the axial center of each socket tube being slightly out of alinement from the center of the opening with which it communicates, so that a portion of the wall of the outer ring as bounded by the opening extends partially across the hollow of the socket tube at the outer end thereof, and a clothes arm provided with a portion to be thrust through an opening into a socket tube, said clothes arm being further provided with a notch for engaging said extending portion of said outer wall as bounded by said opening.

3. A clothes drier for indoor use, comprising a casing having an annular inner wall and an annular outer wall disposed concentrically, the outer wall having a plurality of openings, a plurality of socket tubes connected with said inner wall and extending radially outward therefrom to said outer wall, each socket at its outer end being larger than the adjacent opening and fitting over the same eccentrically, so that the outer wall as bounded by the opening has an edge portion extending slightly across the hollow in said socket, and a clothes arm provided with an end portion to be thrust through an opening and into the tubular socket leading thereto, said clothes arm also having a notch for engagement with said edge portion of the outer wall, to normally prevent the removal of said clothes arm.

4. In a clothes drier for indoor use, the combination of a casing provided with an opening, a clothes arm to be detachably fitted into said opening and thus rendered removable and replaceable relatively to said casing,

- 5 a connecting member mounted upon said clothes arm, and a hand stick provided with a portion for engagement with said connecting member, in order to enable said hand stick to be used for the removal and replacement of said clothes arm. 70
- 10 5. In a clothes drier for indoor use the combination of a supporting member provided with walls spaced apart, one of said walls having an opening, a socket tube extending from one of said walls to the other and partially in registry with said opening, and a clothes arm provided with an end portion for extending through said opening and detachably fitting into said socket tube, said clothes arm being further provided with means coacting with the wall having the opening for normally preventing the withdrawal of said end portion from said socket tube. 75
- 15 20 6. In a clothes drier for indoor use the combination of a supporting member provided with walls spaced apart, one of said walls having an opening, a socket tube extending from one of said walls to the other and partially in registry with said opening, and a clothes arm provided with an end portion for extending through said opening and detachably fitting into said socket tube, said clothes arm being further provided with a notch for fitting over one edge of said opening in order to normally prevent the withdrawal of said clothes arm from said socket tube. 80
- 25 25 7. In a clothes drier for indoor use the combination of a socket tube having the proximate form of a truncated cone, a wall connected with each end of said socket tube, the wall at the larger end of the socket tube being provided with a substantially circular opening of smaller diameter than the adjacent portion of the hollow in said socket tube, and a clothes arm provided with an end portion for extending through said opening and into said socket tube, said clothes arm being further provided with a notch for engaging the edge of the last mentioned wall as bounded by said opening. 85
- 30 30 8. In a clothes drier for indoor use the combination of a supporting member, a clothes arm to be detachably connected with said supporting member, a connecting member carried by said clothes arm and having a substantially bell shaped portion, and a hand stick provided with a tapered end and to be detachably thrust into said bell shaped portion in order to enable the operator to remove and replace the clothes arm. 90
- 35 35 9. In a clothes drier for indoor use the combination of a supporting member, a clothes arm to be detachably fitted to said supporting member, a collar mounted upon said clothes arm and provided with an opening, and a hand stick provided with an end to be detachably fitted into said opening, in order to enable the operator to remove and replace the clothes arm. 95
- 40 40 10. A clothes drier comprising a clothes arm support formed with a substantially vertical wall part, said wall part having an opening therethrough and having a horizontally disposed tubular part extending therefrom as a continuation of said opening, and a clothes arm adapted to be thrust through said opening and into said tubular part, said clothes arm being formed with a notch co-operative with a portion of the support to retain the clothes arm detachably in position. 100
- 45 45 11. A clothes drier comprising a clothes arm support formed with a substantially vertical wall part, said wall part having an opening therethrough and having a horizontally disposed tubular part extending therefrom as a continuation of said opening, said opening being formed to provide a relatively upwardly projecting ledge at the adjacent end of the tubular part, and a clothes arm adapted to be thrust through said opening and into said tubular part, said clothes arm being formed with a notch adapted to interengage with said ledge to retain the clothes arm detachably in position. 105
